UNITED STATES PATENT OFFICE.

CATHERINE GOLAIS, OF NEW YORK, N. Y.

PETTICOAT.

1,059,989.

Specification of Letters Patent. Patented Apr. 29, 1913.

Application filed January 2, 1913. Serial No. 739,768.

To all whom it may concern:

Be it known that I, CATHERINE GOLAIS, a citizen of the United States, residing in the city, county, and State of New York, have 5 invented a new and useful Improvement in Petticoats, of which the following is a specification.

My invention relates to improvements in petticoats and the objects of the invention 10 are to overcome the annoyances incident to the transparency of dress skirts and to devise precautionary arrangements for sanitary purposes, and it consists essentially of the novel construction of the garment 15 more specifically set forth in detail hereinafter, as shown in the drawings, in which—

Figure 1 is a perspective view of the petticoat thrown open to show the interior construction and the sanitary apron partly 20 undone, Fig. 2 is a like view with the front fold thrown back; Fig. 3 is a like view of the front of the petticoat in closed condition; and Fig. 4 is a like view of the back of the 25 petticoat in closed condition.

The petticoat comprises a double ply back 1 extending from the seam 2 to the bottom thereof forming a permanent panel at the rear of the garment, the portion 3 above 30 said panel being a single thickness of material.

4 and 5 are the front folds, the fold 4 extending over the fold 5 at the waist line and therebelow forming a double thickness of material down to the bottom 6 of the 35 petticoat.

7 are fasteners at the waist line for the purpose of closing the petticoat and a plurality of them, suitably spaced, are employed for the purpose of adjusting the petticoat 40 to fit any waist measure. These fasteners may be of the dome or glove type although any suitable form of fastener may be used.

8 is the fastener for the front fold toward the bottom of the skirt.

45 9 are fastener members, preferably of the dome type, arranged along the seam 2 on the inside of the petticoat.

10 are tapes securely sewed to the inside of the back of the petticoat adjacent to the 50 ends of the seam 2.

11 is a detachable sanitary apron having

fastening members 12 co-acting with the fastening members 9 and securing said apron 11 to the back of the petticoat over the double ply 1, said seam 2 forming a secure 55 support for said apron.

13 are tape ends secured to the upper corners of the apron 11 and forming with the tape ends 10 secure ties as an extra precaution against the unfastening of the 60 apron.

14 are tape ends secured to the sides of the apron 11 near the bottom for the purpose of pinning the apron to the garment beyond each side of the apron. 65

The petticoat may be made in various lengths and of any suitable material or combination of materials and may be trimmed in any desired manner.

It will be seen that the garment is of a 70 single thickness over the hips and doubled both front and back, the front fold extending to the lower end, the double ply at the back being full at the lower end in order, with said front fold, to avoid transparent 75 effects. The advantages of the other parts of the invention are obvious and need not be further commented upon.

I claim:—

A petticoat open at the front and folded 80 over at the waist line and therebelow forming a double thickness from the waist line downwardly to the bottom of the petticoat having fasteners at said waist line and a fastener near the bottom of said double 85 thickness and a double ply panel extending from a seam located a short distance below the waist line to the bottom at the back, a detachable sanitary apron secured by fasteners to said seam, tape ends tying said apron 90 to said petticoat at the upper corners and tape ends extending from said apron toward the lower end thereof for the purpose of securing said apron to said petticoat.

In testimony whereof I have hereunto 95 subscribed my name in the presence of two attesting witnesses.

CATHERINE GOLAIS.
